BOREHOLE INCLINATION TRANSMITTER

Donald E. McKee, Fort Worth, Tex., assignor of
one-half to H. F. Spreen, Fort Worth, Tex.

Application May 19, 1936, Serial No. 80,516

3 Claims. (Cl. 177—380)

This invention relates to oil field engineering and it has particular reference to apparatus for accurately directing drilling operations to insure a true vertical course of the bit and its principal object resides in the provision of such a method whereby the minimum of deviation from the vertical can be quickly and easily determined without unduly interrupting drilling operations and thus enabling the operator to make frequent observations and correct any deflections which may occur before they reach major proportions.

Another object of the invention resides in the provision of a device for determining, by audible signals, whether or not the tools are following a true vertical course or the lateral inclination of the bit from a vertical course and the degree of inclination at regular intervals, as the tools progress downwardly, and prevent the usual expensive loss of time and effort in acquiring such information by the use of ordinary clinographs, and the like.

A still further object of the invention lies in the provision of apparatus for orienting oil wells by intentionally deflecting the bit in order to reach a formation remotely situated with respect to the customary vertical course and which can only be negotiated by directing the tools at the required angle accomplished by proper triangulation.

Broadly, the invention seeks to comprehend the provision of a device for audibly determining, at desired intervals, the degree of lateral disposition of the bit and its directional inclinations without pulling the tools or otherwise suspending drilling operations more than a few minutes.

While the foregoing objects are paramount, other and lesser objects will become manifest as the description proceeds, taken in connection with the appended drawings herein.

Figure 1 is a partial vertical cross-sectional view of the upper portion of the apparatus used in effecting the results of the said method illustrating the driving mechanism and the detonating or sound producing elements in the topmost end thereof.

Figure 2 is a vertical cross-sectional view of the middle section of the structure used in carrying out the herein described method showing the mercury switch and the pendulum contact.

Figure 3 is a partial cross-sectional view of the lowermost portion or battery casing.

Figure 4 is a diagrammatic illustration of a battery hook-up for the device.

Figure 5 is a diagrammatic illustration of the complete structure.

Figure 6 is a lateral cross-sectional view of the detonator contact taken on lines 6—6 of the Figure 1.

Figure 7 is a lateral cross-sectional illustration of the gear nest taken on lines 7—7 of Figure 1.

Figure 8 is a lateral cross-sectional view of the spiral-like passage for the quantity of mercury utilized to energize the assembly taken on lines 8—8 of Figure 2.

Figure 9 is a diagrammatic illustration of the wiring circuit of the apparatus.

Figure 10 is a plan view of the upper face of the concentrically arranged contact rings engaged by the lowermost end of the pendulum taken on lines 10—10 of Figure 2.

Figure 11 is an inverted plan view of the pendulum taken on lines 11—11 of Figure 2.

Figure 12 is a view of the cushioning device for the apparatus for supporting the same in the drill stem.

It is highly desirable to project a well downwardly as accurately as possible on a vertical plane so that the various formation above that which is desired to be reached may be negotiated in the most direct course and in order that this may be accomplished it is necessary to determine, at all times, the downward vertical progress of the tools which, under ordinary conditions will vary to some extent at least, from a vertical due to the presence of hard formation and faults which serve to deflect the bit from a straight course and due to the fact that a rotating body when progressed tends to follow a spiral course. Other conditions will necessitate the orientation of the bit to direct the same from a vertical in order to reach a stratum or formation located remotely from the source of the operations, that is, to deflect the bit so as to accomplish a complete well wherein the source of production is found to be situated in an area inaccessible by strictly perpendicular operations.

The herein described invention will enable the operator to adhere consistently to the most direct course in the drilling operations whether it be a strict adherence to the vertical or an angular deviation therefrom, determining the degrees of deviation at predetermined intervals with the minimum of effort and cessation of operations.

The apparatus is especially designed to cooperate with the drilling tools and which consist primarily of a cylindrical casing 1 adapted to repose within a drill stem 2, as illustrated in Figures 1, 2 and 3. The casing 1 receives a housing 3 which contains the assembly of working parts constituting the apparatus utilized in carrying

out the herein described method. The housing 3 is superimposed by an integral dome-like cap 4, as shown in Figures 1 and 5, in the vertex of which is integrally fixed a substantially conical metal element 5 whose functions will presently become manifest.

Within the uppermost end of the housing 3 and partially projecting upwardly into the dome-like cap 4 is situated a solenoid coil 6 housed within the inverted truncated cone-like structure 7 which projects upwardly through an annular opening A in a ring 1' which is welded to the casing 3. The solenoid 6, when energized, operates a plunger 8 at the upper end of which is an integral ball shaped striking element 9 which is brought in contact with the lowermost surface α of the conical member 5 situated in the cap 4 by the solenoid 6 in sharp, quickly executed raps producing a detonation whose sound wave is propagated into the column in drilling fluid and which, under normal conditions, such as moderate depth of the hole and light weight drilling fluids, gives a distinctly audible sound signal at the earth's surface.

Under abnormal conditions, such as extreme depth of the hole or dense and heavy drilling fluids, or other conditions which tend to dampen out the sound signal and render it inaudible to the ear, a simple battery microphone with headphones, is attached at some convenient point on the drilling fluid circulating system to further enable the operator to hear the signal distinctly.

The plunger 8 in the solenoid 6 is provided, at its lowermost end, with a tapered or inverted conical contact member 10 which is attached to the plunger 8 through the medium of a stem 11 projecting upwardly into a recess 12 containing a spring 13 which normally retains the contact member 10 in its lowermost position. The assembly is retained within the recess 12 by means of a pin 14 extending laterally through slots in the lower end of the plunger 8 and through the stem 11 of the member 10.

The solenoid 6, as well as other operating elements incorporated into the apparatus, is energized by a battery of dry cells 15 which is illustrated in Figures 3 and 4. These elements will be described in detail as the description proceeds. A complete wiring circuit is necessary in the proper function of all the parts of the apparatus coordinating to produce the desired results and such circuit will be described in the logical sequence as it relates to the various moving parts and the proper function of the apparatus.

The contact member 10 operates on a vertical plane and, while in its lowermost position, its tapered sides repose within an aperture b formed between two opposingly arranged semi-circular metal plates 16, as shown in Figure 6, whose inner walls are beveled to conform to the tapered surface of the member 10 and thus a connection is completed between the contact member 10 and the plates 16 which are retained in position by bolts or screws 17, as illustrated in Figures 1 and 6, to a supporting plate 18 of a non-conductive material, held in position by bolts or screws 19 threaded into bosses 20.

The plates 16 are separated from the plate 18 by a ring c of non-conductive material and the bosses 20 are integral with a circular insulating plate d. The entire assembly just described is housed within a circular chamber 21 in the upper portion of collar of non-conductive material 22 positioned within the housing 3. One side of the winding of the solenoid 6 is grounded to the cas-

ing 3 through the structure 7. A wire 23 extends from the opposite side of the winding of the solenoid 6 to one of the screws 17, through one of the plates 16 while another wire 24 is connected to the opposite screw 17 and extends through a passage 25 downwardly to the source as will be presently shown.

An annular recess 26 is provided in the lower portion of the collar 22 of non-conductive material which receives the upper end of a cylindrical 10 casing 27 whose lowermost end projects into a ring 28 and rests upon an annular shoulder 29 therein. An electric motor 30 is mounted within the casing 27 and is provided with a vertically arranged shaft 31 which is mounted in bearings 32 and 33 situated within the upper and lower ends of the casing 27 as illustrated in Figure 1. A semi-flexible coupling 34 of non-conductive material is attached to the lowermost end of the shaft 31 which connects the latter with the uppermost end of a shaft 35 which extends downwardly through a gear box 36 which is positioned within a collar 36' and in which is situated a series of reduction gears and pinions which serve to increase the torque and to control the speed 20 of the shaft 35 in the operation of the other mechanism housed within the main casing 3 of the apparatus.

The gear assembly consists of a pinion 37 which is rigidly secured to the shaft 35 just inside the 30 box 36 as illustrated in Figure 1, and is centrally located therein so as to mesh on each side with gears 38 and 39 which are freely mounted upon pins or stationary shafts 40 which extend vertically through the gear box 36 on each side of 35 the pinion 37 and are parallel with the shaft 35. Integral with each of the gears 38 and 39 are pinions 41 and 42 whose teeth engage those of an idler gear 43 freely mounted upon the shaft 35. The pinion 44 integral with the gear 43 meshes 40 with another pair of larger gears 45 and 46 also freely mounted upon the shafts 40, each having integral pinions 47 and 48 which mesh with a larger gear 49 having a downwardly extending hollow integral shaft 50 which revolves around 45 the shaft 35 and within a bearing or boss 51 integral with and extending downwardly from the bottom of the gear box 36.

The integral hollow shaft 50 is slotted at e and receives the upper end of another vertical 50 shaft 52 having a pin 53 extending therethrough whose projecting end extends into the slot e so that the shaft 52 will rotate with the shaft 50 when the latter is driven by the motor 30 through the shaft 31 and the gear assembly in the gear box 36.

The herein described method contemplates the provision as previously stated, of a method for determining the vertical course or the lateral deviation from a vertical course assumed by the 60 perpendicularly arranged drilling equipment and the variation in degrees of such deviation is made known to the operator through a series of tapping or hammering sounds produced by the ball-like head 9 of the plunger 8 striking the 65 under portion α of the member 5 in the dome 4 of the housing 3. The sounds thus produced are carried by the liquid in the drill system to the earth's surface.

Provision is made to afford an arrangement 70 whereby the operator can be definitely apprized of the extent of deviation from a vertical by providing means of causing the plunger 8 to operate at desired intervals and tap the member 5 a number of times and which number may be equal 75

to the number of degrees of deviation plus one, a single detonation signifying a true vertical position of the apparatus. For example, if the deviation amounts to one degree the plunger will operate to tap the member 5 two times at predetermined intervals. If the number of degrees is two the member 5 will be tapped three times at predetermined intervals and so on.

Thus, the shaft 52 extends downwardly through a plate of non-conductive material 54 and a bearing 55 as illustrated in Figure 1, while its lowermost end is received by a bearing 56 disposed within a plate 57 of non-conductive material which is connected to the plate 54 by vertical standards 58 and 59 of non-conductive material. The shaft 52 is surrounded by a metal sleeve 60 which is adapted to rotate therewith and carrying a receiving disk 61 which is arranged above a series of superimposed contact segments, each of which are fixed to and rotate with the sleeves 60, and which are illustrated diagrammatically in Figure 9. The lowermost segment 62 of the series being an intermittent ground connection whose function will presently become manifest.

As illustrated in Figure 9, the receiving disk 61 is provided with a smooth continuous and unbroken outer periphery while the ground contact 62 has an irregular surface around its edge 30 and is provided with a segment extending only a portion of the way around its periphery to provide a sliding contact of intermittent duration. The intermediate rotating contact plates between the receiving disk 61 and the ground contact 62 35 are each provided with extended fingers or contacts projecting axially therefrom and which are contacted by spring tensioned arms 64 to which the wires f, g, h, i, j and k are connected from the source.

Figure 9 shows the segment or contact disk 65 immediately beneath the receiving disk 61 as having only one contact finger 63 while the disks 66, 67, 68 and 69 are shown as having two, three, four and five contact fingers 63 respectively. As the shaft 52 is rotated, therefore, the tensioned contact arms 64 will engage the fingers 63 of the segments intermediate the receiving disk 61 and the ground segment 62 and intermittently energize the solenoid 6 through the receiving disk 61 50 and the line 24.

The arrangement of the disks 65 to 69, illustrated diagrammatically in Figure 9, on the shaft 52 and the sleeve 60, is such that the contact sequence of the fingers 63 with the spring tensioned arms 64 thereof is such that the first of the series of fingers 63 on each of the disks 65 to 69 will engage the tensioned arms 64 thereof simultaneously when the disks are rotated anti-clockwise. It is pointed out that there are provided five of these elements, each having, respectively, from one to five contact fingers 63. Thus, when the single contact finger 63 of the disk 65 is in contact with its tensioned arm 64, the first finger 63 of each of the other disks 66 to 69 are also in engagement with their respective arms 64. When this contact is broken as the disks rotate, the second contact finger 63 of each of the disks 66 to 69 are in simultaneous engagement with their respective arms 64 until their rotation causes the breaking of such contact and the third contact fingers 63 of the remaining three disks 67 to 69 are in simultaneous engagement with their respective arms 64 and whereupon, as the disks rotate, the fourth fingers 75 63 of the disks 68 and 69 come into simultaneous

contact with their arms 64 and, finally, the last contact is made through the fifth contact finger 63 on the last disk 69.

The ground segment 62 is positioned and timed on the sleeve 60 in such a manner as to close its circuit before the first contacts 63 of the disks 65 to 69 close with the spring tensioned arms 64 and to hold this circuit closed until after the fifth contact 63 of the disks 69 has closed with the spring tensioned arm 64 and then opened, as illustrated diagrammatically in Figure 9. It will be noted from reference to Figure 9, that the segment 62 is fully insulated from the shaft 52, the sleeve 60 and the disks 61, 65 to 69 by the insulator m.

The assembly is designed to be a self-contained water-tight appliance which reposes within the drill stem during all normal drilling operations and to be removed only at such times as battery replenishment is necessary, or at such times as it is desirable to ream the hole, take cores, and the like.

To be effective the assembly is placed within the drill stem 2 in as close proximity to the drill bit, as is practical. Therefore, the assembly is designed to fit within a special section of hydraulic pipe which is fitted with tool joints and which connects to the drill collar at the extreme bottom of the drill stem. Ample space for the circulation of drilling fluid is provided for by the circular passage 2' between the drill stem 2 and the casing 1, shown in Figures 1, 2 and 3.

With the assembly in proper position within the drill stem, any rotary motion, clockwise or anti-clockwise, of the drill stem 2, is transmitted to the assembly by the apparatus shown in Figure 12, therefore, the assembly rotates with the drill stem as the latter is operated within the well in its different operations in drilling. This rotary motion is made use of for controlling the appliance and to bring the same into operative or inoperative positions.

The rotary clockwise rotation of the drill stem 2 as in drilling, tends to cause the appliance to assume the silent or off position. Therefore, to cause the appliance to function to propagate a signal the drill stem is brought to rest from clockwise rotation, then rotated clockwise one or two revolutions to effect the closing of the circuit which energizes the motor 30 and the solenoid 6.

The circuit, as illustrated in diagrammatic detail in Figure 9, is energized by a quantity of mercury which is caused to come to rest between two non-amalgamating metal contacts to complete the circuit and which is dislodged by the rotation of the drill stem 2 as will be presently shown.

The main switch, therefore, consists of a substantially solid cylindrical mass of non-conductive material which is comprised of an upper section 72 and a lower section 73, each of which is provided with a spiral like groove 74, as is shown in Figure 8, which communicates at one end with a concave recess 75, situated near the outer edge of the section, and terminates in a central recess 76. Thus, when the two sections are assembled as shown in Figure 2, a spiral-like passage 77 is provided within the member 71 and a chamber 78 is formed in the center of which is provided by the recess 76 in each of the members 72 and 73, as shown in Figure 8.

The lower section 73 of the assembly 71 is surrounded by a ball race 79 of metal to accommodate ball bearings 80 which operate within a race 81 also of metal and which surrounds the 75

lowermost end of the member 73 and rests upon a metal ring 82 which reposes within an annular recess 83 in the upper end of a collar 84 of a non-conductive material. Another collar 85 of 5 an insulating material is situated immediately above the collar 84 and provides an insulated casing for the switch assembly 71 which is covered by a circular plate 86 secured to the collar 85 by screws 87. The collar 85 is fixed to the 10 housing 3 by screws 85', or the like.

Extending downwardly through the upper section 72 of the assembly 71 is a stem 88, which is secured to the member 72 by lock-nuts 89, terminating within the recess 78 in a contact 15 point 90 which is of a substantially inverted cone-shaped structure having a concave surface. Immediately beneath the contact 90 and spaced apart therefrom is provided another contact 91 which extends upwardly through the section 73 20 terminating in the bottom of the chamber 78 and which is integral with the retaining plate 79' and which retains the section 73. The retaining plate 79' is provided with an integral boss 92 which projects downwardly opposite the 25 contact 91, just described, and whose under surface is provided with a concave face 93 whose function will be presently described.

In the lower portion of the collar 84 another annular recess 94 is provided to receive a metal 30 collar 95 which comes in contact with and retains in position a metal ring 96 whose inner face is concave and which is adapted to serve as a race for balls 97 whose inner face 98 is secured to and surrounds a head 99 of a pendulum 100. The concave face of the ring 96 affords a liberal surface under which the bearings 97 may freely operate therearound or laterally, with respect to a common circular course, thus providing a universal action of the bearing 40 allowing the head 99 of the pendulum 100 to rotate as well as to swing from side to side. The ring 96 is separated from the retaining collar 101 by insulating material 102. The collar 101 supports the assembly, as illustrated in Figure 2, and which is welded, or otherwise secured 45 within the casing 3.

Projecting upwardly from the head 99 of the pendulum 100 is provided a hollow nipple 103 in which is situated a plunger 104 supporting a ball 105 and which normally urges the latter, by reason of a spring 106, against the concave undersurface 93 of the boss 92. It will be noted that by reason of the fact that the face 93 of the boss 92 is concave, the ball 105 may closely contact the surface at any point of its area since it is capable of being moved under the surface in any direction by reason of its association with the head 99 of the pendulum 100 which is capable of circular or lateral movement in any direction due to the manner in which it is suspended by the bearing assembly 96, 97, and 98.

As stated, a suitable quantity of mercury is deposited within the recess 75, shown in Figure 8, when the sections 72 and 73 of the switch 65 71 are assembled and it is free to travel in the spiral-like passage 77 which graduates downwardly from the recess 75 to the central chamber 78 where it provides an electrical connection between the contacts 90 and 91, thus completing a circuit through the retaining plate 79', the ball race 79, the ball bearing 80, the outer race 81, the metal rings 82 and through the flexible wire connection 107 attached thereto which extends to the motor 30 as shown in Figure 1, providing a positive connection to the 75

motor windings. The negative side of the motor winding is grounded to the casing 3, as shown in Figure 9.

With the rotation of the motor 30 the contact segment 62, shown in Figure 1 and the diagrammatic Figure 9, closes the contact with the two lower spring tensioned contacts 64 thereby energizing the pendulum circuit. The electrical circuit is then completed through the boss 92 and the ball 105 contacting the concave face 10 93 through the plunger 104 and the spring 106 which is in direct contact with the metallic conduit 99' extending downward through the center of the pendulum 100 to the bob 111. This circuit is further carried through the metallic conduit 99' to the positive side of the windings of the solenoid 110, and is also connected to the solenoid plunger 112 through the spring 113 as shown in Figures 2 and the diagrammatic illustration in Figure 9. 20

A negative connection for the solenoid 110 is also provided in an insulated wire connection 109 which is secured at one end to the negative side of the solenoid winding and extends upwardly through the metallic conduit 99' of the pendulum 25 100 to the retaining plate 108, as is shown in Figure 2. The circuit thus provided is completed through the race 98, the ball bearing 97, the outer race 96, the metallic ring 95 and the insulated wire connection 114 to the spring tensioned contact 64, through the contact segment 115 (62) to the opposite spring tensioned contact 64, and thence to the casing 3, as is shown in Figure 2 and in the diagrammatic illustration in Figure 9. 35

It will be noted by reference to Figure 9 that this circuit is open and closed by the contact segment 115 (62) rotating in proper sequence with the disks 65 to 69, and that this circuit is closed over a sufficient period of time to allow any 40 and all of the contact points 63 on the disks 65 to 69, to make complete contact with the spring tensioned contacts 64 and to fully complete their respective circuits.

It is also pointed out that through this intermittent energizing of the solenoid 110 in Figure 2, that the plunger 112 and a contact point 117 are periodically released from contact position, thus the pendulum 100 in the bob 111 will be freed periodically to readjust their position in 50 any event that the first contact point selected is not in a true vertical line. It is further pointed out that this intermittent flow of electrical current tends to conserve battery energy. 45

As shown in Figure 2 and the diagrammatic 55 illustration in Figure 9 the solenoid 110 is provided with a plunger 112, which, when the solenoid 110 is not energized, is normally retained in its uppermost position by the coil spring 113. This plunger 112 preferably comprises a thin brass 60 tube closed to a sharp conical shape at its lowermost end 117, the upper half being filled with a soft iron core secured within the latter, which gives positive downward pressure to the plunger 112 against the action of the coil spring 113 65 when the solenoid 110 is energized and a magnetic field is set up within and surrounding the windings of the solenoid 110. This downward movement of the plunger 112 causes the contact point 117 to engage and impart positive battery 70 potential to some selected metallic point on the selector plate 117, as shown in Figure 2.

The contact 90 extending into the chamber 78 is connected directly to a line 116 which extends to the source, as shown in Figure 3 and in the 75

diagrammatic Figure 9, which will be presently described. An inverted plan view of the pendulum 100, taken on lines 11—11 of Figure 2, as shown in Figure 11.

- 5 The position of the pendulum 100, that is, the suspended position of the bob 111 thereof, controls the audible signalling apparatus through the medium of the member 5 in the dome 4 of the casing 3 when contacted by the striking element 9 actuated by the solenoid 6. The bob 111 of the pendulum 100 is secured to the lowermost end of the latter in such a manner as to enable its vertical adjustment thereon so that the lowermost projecting end or contact point 117 of the 10 plunger 112 will be suspended above the stationary contacts in relatively close proximity thereto so as to insure the proper function of the contact when the contact point 117 comes to rest above any one of the stationary contact rings. 15
- 20 The selector plate 117 just referred to is positioned immediately below the bob 111 of the pendulum 100, as shown in Figure 2, and consists of a ring 118 of non-conducting material wherein is concentrically arranged a series of metal 25 rings, 119, 120, 121, and 122 which are separated by annular rings of insulating material 123, as shown in Figures 2 and 10.

In the center of the assembly is a single round core 123' which is also of metal. The assembly 30 is secured within the casing 3 by means of an annular collar 124 which is welded or otherwise secured to the casing 3 and is provided with a recess in its lowermost side to accommodate the assembly, as illustrated in Figure 2. The upper 35 face of the assembly is concave and each of the insulating rings 123 extend slightly above the metal contact rings 119 to 122, as well as the core 123', to form relatively sharp annular ribs 1 which act to guide the contact engagement on 40 the selected contact ring or core when the solenoid 110 is energized and the plunger 112 is urged downwardly bringing the contact point 117 into engagement therewith. Another important feature of the sharp upwardly projecting ribs 1 is 45 in the angular faces thereof as shown in Figure 2, which function to impart a sliding or lateral movement to the contact point 117 of the plunger 112 as it is forced into contact position with the selected point on one of the contact rings 119, 120, 121, and 122 or the metal core 123'. This sliding or lateral movement of the contact point 117 insures a clean and positive electrical contact between the latter and the selected contact.

55 When a signal is desired, it is very important that the signal propagated by the apparatus will signify with moderate accuracy the true position of the pendulum 100 and the bob 111 with respect to a vertical, in relation to the casing 1 and the drill stem 2, thereby indicating with reasonable accuracy the actual position of the drill stem in relation to a true perpendicular or vertical position.

The selector plate 117 shown in Figures 2 60 and 10 is comprised of the metal core 123' and the concentrically arranged metal contact rings 119, 120, 121, and 122, and spaced apart by the insulating rings 123 in such a form and position in its relation to the pendulum 100, the bob 111 65 and the contact point 117 as shown in Figure 2, that when the contact point 117 engages the core 123' as signal of one detonation is propagated at regular intervals indicating an approximate perpendicular position for the drill stem. If the contact point 117 should engage a point on a con-

tact ring 122, a signal of two detonations is propagated, indicating an inclination of the drill stem of approximately one degree from perpendicular.

In other words, the selector plate 117 is so designed, formed and positioned in its relationship with the pendulum 100 the bob 111 and the contact point 117 that should the drill stem 2 incline from a perpendicular position two degrees the contact point 117 will be suspended directly 10 over some point on the contact ring 121 and should the drill stem incline from a perpendicular position three degrees the contact point 117 will be suspended directly over some point on the contact ring 120 and so on. Therefore it will be 15 seen that the audible signal generated by an appliance of this particular design, is indicated in whole degrees and not in fractions thereof.

It is the purpose of the herein described device to indicate the actual position of the drill 20 stem in its relationship to a true perpendicular or vertical within approximately one-half ($\frac{1}{2}$) degree of accuracy.

This is accomplished mainly by providing guides for the contact point 117 in the form of the inverted V-shaped upper ribs 1 of the insulating rings 123 separating the contact rings 119 to 122 and surrounding the core 123'. These elements, by reason of their downwardly inclined opposing faces, assist in directing the contact point 117 30 into engagement with one of the contact rings 119 to 122 on each side thereof, as well as the core 123'. The assembly is illustrated in Figures 2 and 10 and diagrammatically shown in Figure 9. 35

To more clearly indicate the function of the upwardly projecting ribs 1 of the insulator rings 123, it may be stated that should the drill stem, in its downward course, actually assume an inclination from a vertical of the order of 2.75 degrees, the pendulum 100 will assume a true perpendicular position when drilling operations are ceased, that is, when the rotation of the drill stem has ceased rotation. Obviously, if the drill stem has deviated from a vertical, the bob 111 40 secured to the lowermost end of the pendulum 100 will assume a position above the third of the insulator rings 123 and sufficiently past the rib 1 thereof to cause the point 117 to be deflected downwardly into contact with the third contact 45 ring 120.

When the apparatus is energized, therefore, the solenoid 110 in the bob 111 will operate to urge the contact point 117 downwardly to engage the contact ring above which it is suspended or 55 cause the same to engage the rib 1 thereunder or one of its inclined faces and be directed downwardly thereby to contact the surface of one of the rings 119 to 122 depending upon which side of the rib 1 the contact 117 first engages. The 60 contact point 117, to be better suited for the function just described, is provided with a relatively blunt rounded lower end to better enable its deflection by the inclined surfaces of the insulator rings 123. 65

It will be noted, that since the several contact disks 65, 66, 67, 68 and 69 must operate in sequence to transmit the proper signal, the connections f, g, h, i, and j extend to the tensioned arms 64 which contact the disks aforesaid, as shown in 70 Figure 1. The wire connections f to k shown in Figure 1, extend downwardly through the casing 3 through a conduit 125, as shown in Figure 2. The wire connection k, shown in Figure 1 to be connected to the lowermost of the tensioned arms 75

64 of the ground segment 115 (62) and shown in Figure 9, serves as a ground connection, for the controlling circuit of the solenoid 110.

Referring more in detail to the pendulum 100
 5 it is pointed out that the latter is provided with an integral circular portion 126, as shown in Figure 2, and beneath which extends four integral guides or fins 127, which taper inwardly toward the bottom of the pendulum 100, and which extend 10 laterally and radially from the metallic conduit 99' which is arranged longitudinally through the center of the pendulum 100. This assembly with the exception of the metallic conduit 99' is made up of a tough, strong, non-conducting and non- 15 magnetic material. The bob 111 may be made of brass or the like, being substantially conical in form and is provided with a chafing ring 128 as is shown in Figure 2, of rubber or the like, to afford a bumper or shock absorbing medium to 20 prevent the bob 111 from coming into sharp contact with the inner walls of the casing 3, should the pendulum 100 oscillate abnormally from shock or motion of the drill stem while in operation, or from handling the apparatus while out of 25 the drill stem.

It is further pointed out that the pendulum assembly is so designed that the major portion of its inherent weight is concentrated within the bob 111 at the bottom of the assembly as is shown 30 in Figure 2. Therefore, suspended as it is, by the universal ball bearing assembly 96, 97 and 98, as shown in Figure 2, the pendulum assembly has a strong tendency to maintain a true vertical position under all operating conditions, when the 35 appliance is properly positioned within the drill stem. Further attention is directed to the fact that as the appliance is rotated by the drill stem 2 as in drilling, very little rotating torque can be actually transmitted through the universal ball 40 bearing assembly 96, 97 and 98 as shown in Figure 2 from the casing 3 and the metal retaining collar 101 to the pendulum assembly.

Therefore, in relation to the rotating speed of the drill stem 2 and the casing 3 and the metal 45 retaining ring 101, shown in Figure 2, the rotating speed of the pendulum assembly is very slow in comparison, and for this reason the bob 111 of the pendulum 100 is never subjected to centrifugal forces of any great magnitude, which might 50 tend to throw it into contact with the casing 2 while being rotated and which in turn would cause undesirable lateral oscillation of the pendulum assembly as the drill stem has ceased rotation and which would further tend to delay accurate 55 signalling.

The source of electrical energy for operating the device consists of a series of dry cells 15 previously referred to, which are properly housed within the lower portion of the casing 3, as illustrated 60 in Figures 3 and 4. It will be noted, by reference to Figure 4, that the battery is made up of dry cells 15 connected in parallel series to provide a battery with a sufficient load potential and capacity for efficient operation. The assembly of 65 the cells 15 is such as to provide a simple, practical and positive energy source which can be conveniently replaced when necessary. As illustrated in Figure 4, several dry cells 15 are grouped and connected in series to provide each of the three 70 parallel circuits of the battery. Each series of the dry cells 15 illustrated in Figures 3 and 4, are inserted into a protective case 132 of durable insulating material. As shown in Figure 3, each cell 15 is separated and cushioned by the flat ring 75 of rubber or other suitable material 131.

The spring tensioned contact 129, illustrated in Figure 3, is positioned near the lower extremity of each of the three insulating tubes 132 which surround and house each group of the five dry cells 15, and preferably is fixed thereto to provide 5 a positive contact with the negative pole, or the outside case of the lowermost dry cell 15 of each group and to afford a ground connection to the casing 3. The coil spring contact 129' functions as a ground connection for the lowermost group 10 of dry cells. As illustrated in Figure 4, the three positive connections for the three parallel circuits incorporated into the dry cell arrangement of the battery are so arranged as to make proper electrical connections with the positive post 130, 15 through the latter to the main positive circuit 116, and thence through the latter to the switch 71, illustrated in Figures 2 and 9.

As illustrated in Figure 3, a contact is made 20 between the dry cells 15 and the post 130 through a flanged metal plate 133 which bears against the head portion 130' of the post 130 and which is retained in the annular recess *n* of an insulating collar 134 by an insulating ring 131 atop the dry cell 15.

The contact post 130 projects upwardly through a central aperture in a circular plate 135 which is provided with a boss 135' projecting downwardly through an opening in a metal ring 136 which is welded to the walls of the casing 3 and provides a partition therein as well as an anchor for the assembly. A spring 137 affords a tensioned contact between the positive post of the uppermost dry cell 15 and the plate 133, as well as affording a series connection between each dry 35 cell 15 of each group.

The circular flanged member 133, as shown in Figure 3, is connected to the flexible conductor 133' which extends downwardly through the conduit 136' in the battery casing 132 to a similar 40 flanged member 133 at the top of each series of dry cells, shown at *o* and *p* in Figure 4.

In each case as shown in Figure 3, the circular flanged members 133 are retained in position in the assembly between a disk of insulating material 131 thereabove, of ample thickness, and a flat insulating ring 131' therebeneath. Electrical contact between the circular flanged member 133 and the positive pole of the top dry cell of each group is maintained by a spring 137. Thus it will 50 be seen that the cell group is provided with three positive parallel circuits which make proper electrical connection with the positive post 130, shown in Figure 3, when the battery assembly is in proper position in the lower end of the casing 55 3. It is further pointed out that when the battery assembly is properly placed within the cavity provided therefor at the lower end of the casing 3 and the cap 138, shown in Figure 3, is threaded 60 upwardly and the contacts are made more secure. The rings 131 and 131' are compressible and absorb shock and vibration.

In practice, therefore, the invention is assembled as aforesaid and positioned in close proximity 65 to the drill bit in the lowermost portion of the drill stem 2, which in turn is lowered into the well for the usual drilling procedure.

As drilling operations progress the operator may, when desirable and from time to time, and 70 without removing any part of the drill stem, cause the device to function by stopping the drilling operations and rotating the drill stem one or two revolutions in a clockwise direction. As shown in Figure 2, the first operation of bringing 75

the drill stem to a state of rest, will cause the switch assembly 71 to continue a clockwise rotation by reason of the momentum imparted thereto, until the upwardly projecting lug 139 engages 5 the spring tensioned stop 140, positioned atop the retainer plate 86, when it is brought to a cushioned stop.

Since very little rotating torque can be transmitted to the switch assembly 71 through the ball bearing assembly 79, 80 and 81 shown in Figure 10 12, when the drill stem is again rotated one or two revolutions clockwise the switch assembly 71 will remain stationary while the collar 85 carrying 15 the retaining plate 86 rotates with the casing 3 until the stop 140 is brought to a sharp contact with the lug 139 and the sudden impact against the latter forces the mercury imprisoned within the spiral-like passage 77 from the pocket or cavity 75 from whence it travels downwardly 20 and around therethrough into the chamber 78 where it provides a connection between the contact point 90 of the stem 88 and the connection 91. As illustrated in Figures 2, 3, 4 and 9, the contact point of the stem 88 of the switch assembly 25 71 is connected electrically by the flexible wire connection 116 to the positive post 130 of the battery assembly.

Therefore, when the contact point 90 and the connection 91 of the switch assembly 71 are connected in this manner by the globule of mercury, as above described, the motor 30, shown in Figure 1, is energized through the integral connection 91 of the retainer plate 79' which is in contact with the bearing assembly 79', 80 and 81 35 and the latter being in contact with the metal ring 82 to which the flexible connection 107 is attached and which extends upwardly through the passage 25, as shown in Figure 1, the current is transmitted to the positive terminal of the motor 40 38 which latter is grounded to the casing 3 to provide a negative return circuit to the battery assembly, as shown in the diagrammatic illustration in Figure 9.

The motor 30, when energized, will function to 45 rotate the shaft 31 and the gear assembly in the gear box 36 transmitting rotation through the shafts 35 and 52 to the sleeve 60 bearing the metal contact disks 65 to 69, the receiving disk 61 and the contact segment 115 (62), all of the latter being integral with the sleeve 60 except the ground segment 115 (62), as hereinbefore stated.

The function of the contact disks 65 to 69, shown in Figure 1, is directly connected with that of the pendulum 100, shown in Figure 2, through 55 the medium of the contact rings 119 to 122 and the core 123'. When the bob 111 of the pendulum 100 is suspended in a vertical position within the casing 3, as shown in Figure 2, the same will be above and in close proximity to one of the circular contacts 119 to 122, or the core 123', depending upon the inclination of the casing 3 and the drill stem 2.

By rotation of the motor 30 the contact segment 115 (62) closes the circuit through the two lower spring tensioned arms 64, thereby energizing the solenoid 110, shown in Figure 2, operating the plunger 112 and transmitting positive battery potential therethrough. The electrical circuit is then completed through the boss 92, 70 shown in Figure 2, the ball 105 contacting the concave face 93, through the plunger 104 and the spring 106 which latter is connected with the metallic conduit 99' extending downwardly through the center of the pendulum 100. The 75 circuit is transmitted through the metallic con-

duit 99' to the positive side of the winding of the solenoid 110, and to the plunger 112 through the spring 113.

The negative contact for the solenoid 110 is provided in a flexible insulated wire connection 5 109 and extends upwardly through the metallic conduit 99' of the pendulum 100 to the retaining plate 108, shown in Figure 2. The circuit thus provided is completed through the ball bearing assembly 98, 97, and 96 to the metal ring 95 and 10 the insulated wire connection 114, through the latter to the spring tensioned contact 64 contacting the segment 115 (62) and through the latter to the opposite spring tensioned contact 64 and thence to the casing 3, in the manner illustrated in Figure 9.

When the solenoid 110 in the bob 111 is energized, as above described, the plunger 112 will be urged downwardly causing the contact point 117 to engage one of the circular contacts 119 to 123', 20 depending upon the inclination of the casing 3 in the drill stem 2, and energize the same, completing the circuit through one of the contact disks 65 to 69 and one of the circuits f, g, h, i and j and the corresponding spring tensioned contacts 25 64. The circuit will thus be transmitted from the contact disks 65 to 69 through the sleeve 60 to the receiving disk 61, and thence through the flexible wire connection 24 to the contact 10 of the solenoid 6 to operate the plunger 8 upwardly, 30 causing the detonator 9 to impart a series of sharp taps against the under surface a of the member 5 fixed in the dome 4 of the casing 3. Electrical energy is transmitted through the cylindrical casing 60 surrounding the shaft 52 but, 35 as shown in Figure 9, the ground contact 115 (62) is insulated from the sleeve 60 at m.

The device will operate to produce the audible signal hereinbefore described at regular intervals 40 so long as the motor 30 continues to function and its electrical circuit remains unbroken. The circuit of the latter will not be broken or opened, until the apparatus is rotated by the action of the drill stem 2 and a sufficient momentum is imparted to the switch assembly 71 to displace the 45 mercury from the chamber 79 and cause the same to return through the spiral like passage 77 to the cavity or pocket 75 in which it normally reposes, as shown in Figures 2 and 8.

Once the mercury is displaced from the chamber 78 in the switch assembly 71 the metallic contact is broken between contact point 90 and the connection 91 and between the positive connection of the battery and the various circuits of the assembly. The solenoid 6 is energized only 55 as the contact fingers 63 on any one of the disks 65 to 69 are energized and transmit such energy through the tensioned arms 64, shown in Figure 1, through the receiving disk 61 and the arms 64 to the contact 10 of the solenoid 6. 60

When assembled the device is placed within the lowermost section of the drill stem 2 and is cushioned upon a shock absorber, illustrated in Figure 12, and which consists of a spider 141 integrally fixed within the drill stem 2 and which is provided with a central body 142 having a square opening therethrough accommodating a square vertically arranged shaft 143 to whose uppermost end is integrally fixed another central body 144 having radial fingers 145. A cup-like member 146 is integrally attached to the uppermost side of the body 144 and is adapted to receive the integral lug 147 of the threaded plug 138 of the casing 3. A coil spring 148 surrounds the shaft 143 and the weight of the entire as- 75

sembly, including the apparatus herein described, bears upon the spring 148 whose lowermost end rests upon the body 142 supported by the spider 144 as previously described. The shaft 143 is 5 free to move vertically through the body 142 and thus afford a shock absorbing or cushioning device for the assembly. A cap or collar 149 is secured to the lowermost end of the shaft 143 by a pin 150, or the like, to prevent the shaft 143 from 10 becoming dislodged therefrom.

The device is lowered into the hole within the drill stem 2 and submerged within the drilling fluid and its actual submerged weight tends to lessen with depth, and in proportion to the increased density of the drilling fluid. As mentioned hereinbefore the apparatus is concentrically retained within the drill stem 2 by the radial lugs 70 which are integral with the casing 3, as illustrated in Figures 1, 2 and 3, and sufficient 15 clearance exists between the lugs 70 and the inner walls of the drill stem 2 to permit free longitudinal movement of the device within the latter when necessary.

Since the device is urged downwardly against 20 the shock absorber assembly only by its own submerged weight, coupled with the frictional action of the downward movement of the drilling fluid, any momentary upward force from below which is greater than the forces which tend to urge the 25 device downwardly in position upon the shock absorbing apparatus will spend itself harmlessly in the drilling fluid for the reason that the device will merely be suspended within the fluid momentarily. It is apparent, therefore, that any shock 30 or series of vibrations which are transmitted to the drill stem from the drill bit or other sources, can not be transmitted in any series proportion to the apparatus. The lugs 70, as shown in Figures 1, 2 and 3 are integral with the casing 3 near 35 the uppermost and the lowermost ends of the assembly. Any twisting or bending of the drill stem 2 is not transferred to the casing 3 at any point.

Inasmuch as the dome-like structure 4, shown 40 in Figure 1, is subjected to destructive abrasive action from the solid matter suspended in the drilling fluid this member is enveloped in a protective coating of rubber, or the like, and in such a manner that, while the dome 4 is fully protected, 45 the conical member 5 is exposed and extends into the drilling fluid.

The drilling fluid consists largely of water under all ordinary conditions in rotary drilling and the water content of the drilling fluid is an excellent sound conducting medium. That portion 50 of the drilling fluid which is made use of for conducting the primary sound wave to the earth's surface, is the column of drilling fluid which is confined within the steel drill stem. Therefore, 55 when the impact of the member 9 shown in Figure 1, against the conical member 5, is transferred into sound waves and propagated into the column of fluid confined within the drill stem, the latter functions as a resonator to further strengthen each sound wave in its propagation in 60 the column of drilling fluid to the earth's surface. As hereinbefore mentioned, under abnormal conditions in drilling, such as the extreme depth of the device in the well, or other circumstances which necessitate circulation of heavy drilling 65 fluids while drilling, or other conditions wherein

the sound signal is partially damped out and rendered inaudible to the ear of the operator, a simple battery microphone with headphone is attached to some convenient point on the drilling fluid circulating system to enable the operator to 5 audibly pick up the propagated signal distinctly.

Simple detonations are made use of in signalling with the apparatus so that the signal is distinct and apart from the other normal oscillating sounds arising from circulation of the drilling fluid, the operation of the pumps, and the like.

Although the invention has been described with great particularity, it is obvious that certain changes and modifications may be resorted to from time to time by those skilled in the art and such changes and modifications may be considered within the spirit and intent of the invention, and may also be considered as coming within the scope of the appended claims.

What is claimed is:

1. A borehole inclination transmitter comprising a casing capable of insertion in a borehole, a pendulum within the casing and suspended for universal motion therein, a contactor 25 on the pendulum at the extremity thereof, a plurality of concentric spaced contact rings positioned in cooperable relation to the contactor on the said pendulum, a multiple code transmitter means, means under the control of said transmitter means for striking the casing in conformance with a code, circuit means controlled by the engagement of the contactor with a contact ring for selecting the code transmitted by the transmitter means.

2. A borehole inclination transmitter comprising a casing capable of insertion in a borehole, a pendulum within the casing and suspended for universal motion therein, an extensible contactor on the pendulum at the extremity thereof, a plurality of concentric spaced contact rings positioned in cooperable relation to the extensible contactor on the said pendulum, a multiple code transmitter means, means under the control of said transmitter means for striking the casing in conformance with a code, means for extending the extensible contactor to engage any contact ring which is adjacent thereto, circuit means controlled by the engagement of the extensible contactor with a contact ring for selecting the code transmitted by the transmitter means.

3. A borehole inclination transmitter comprising a rotatable casing capable of rotation and insertion in a borehole, a pendulum within the casing and suspended for universal motion therein, an extensible contactor on the pendulum at the extremity thereof, a plurality of concentric spaced contact rings positioned in cooperable relation to the extensible contactor on the said pendulum, a multiple code transmitter means, means under the control of said transmitter means for striking the casing in conformance with any code, rotation controlled means for extending the extensible contactor to engage any contact ring which is adjacent thereto upon the cessation of rotation, 65 circuit means controlled by the engagement of the extensible contactor with a contact ring for selecting the code transmitted by the transmitter means.

DONALD E. MCKEE. 70
